US0D1026508S

(12) **United States Design Patent** (10) Patent No.: **US D1,026,508 S**
(45) Date of Patent: ** May 14, 2024

(54) **BOTTLE ORGANIZER**

(71) Applicant: **Wei Yu**, Foshan (CN)

(72) Inventor: **Wei Yu**, Foshan (CN)

(**) Term: **15 Years**

(21) Appl. No.: **29/902,967**

(22) Filed: **Sep. 19, 2023**

(51) LOC (14) Cl. **07-02**

(52) U.S. Cl.

USPC **D7/701**; D6/675.1

(58) **Field of Classification Search**

USPC D6/672, 675, 675.1, 682, 682.2, 682.4,
D6/514; D7/701, 708, 600.4, 619.1;
D15/89

CPC A47G 23/02; A47B 73/00; A47B 81/007;
A47F 7/283

(57) **CLAIM**

The ornamental design for a bottle organizer, as shown and described.

DESCRIPTION

FIG. 1 is a top perspective view of a bottle organizer showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof; and,

FIG. 8 is a top perspective view of a bottle organizer in an environment of use.

The broken lines in the drawings depict environmental structure that form no part of the claimed design.

1 Claim, 8 Drawing Sheets
